UNITED STATES PATENT OFFICE.

ELLIOTT B. MABEE, OF BROOKLYN, NEW YORK.

ILLUMINATING DEVICE.

Application filed March 18, 1924. Serial No. 699,985.

My invention relates to illuminating devices which are particularly adapted for medical and dental uses.

Its object is the production of a novel type of lamp which comprises in one structure means for either concentrating its light in parallel rays, that is, a spot light, or directing the same in evenly diffused wide angle rays, or permitting the employment 10 of the whole power of the light source to create a flood or open light.

Another object of the invention is to permit the ready employment or adjustment of either of these means by a simple manipulation of one or two elements of my device.

Another object of the invention is to prevent the emergence of the light from any part of the device except where intended. This is accomplished by the overlapping of 20 the ends of the hemispherical members hereinafter described.

Another object of the invention is to allow instant access to any part of my device for change or replacement of light source, 25 cleansing of parts, or for any other purpose.

Other objects and advantages will appear from the following detailed description and the accompanying drawings forming part hereof.

30 My improved structure is preferably made of metal, and, as shown, comprises a reflector member in which the light source is positioned in any suitable way. Two substantially similar elements, larger in circumference than the reflector member, are arranged to be independently rotatable over the same. One of these is adapted to receive a diffusing material, preferably prismatic glass, and the other a lens system. The 35 whole is mounted on a bracket or floor stand by which it may be placed wherever desired.

Referring to the drawings, Figure 1 is a vertical section, and Figure 2 a horizontal section of my new device; Fig. 3 is a 40 sectional view of another form of mounting for the lens system.

Similar reference characters refer to corresponding parts.

The bracket arm by which the lamp is 50 supported is designated by the numeral 1, or the device may be supported by socket 9. The bracket arm may be of any desired form so long as it does not impede the movement of the diffused glass and lens-bearing 55 members. In the ends of the bracket are bolts 2. On these bolts are situated mem-

bers 3, 4 and 5. The member 3 is preferably stationary, and is located on the inner ends of the bolts, and intermediate said stationary member and the ends of the bracket, 60 are mounted movable members 4 and 5. Each of these is substantially hemispherical in form. Nuts 6, 7 and 8 hold them in place, and spring washers 19 and 20 serve to exert the tension needed to maintain 65 members 4 and 5 in their relative positions.

The member 3 acts as a reflector, and is apertured to receive socket 9 and electric lamp 10. To hold the socket and lamp in place the wall of member 3 may be turned 70 inward as at 11, with which inturned part split ring 12 co-operates for the purpose stated. The interior of member 3 is preferably given a high polish, or its reflecting power may be enhanced in any other 75 way desired.

The member 4 is cut away to receive the prismatic glass or light-diffusing material 13, the parts 14, in conjunction with encircling wire 15 co-acting to hold the said glass 80 in place in any position of the member 4.

The member 5 is extended at its centre into a tubular portion 16 in which are located one or more lenses 17 and 18. These lenses may be mounted in any way desired, 85 and not necessarily directly and removably attached to member 16. In Fig. 3, for instance, I have illustrated a mounting devised by me which is simple and economical in construction, and has the advantage of 90 permitting both lenses to be removed through the outer end of extension 16. This mounting consists of a sleeve 24 provided at one end with a slight flange 25 to engage the circumference of member 16. A threaded 95 retaining cap 26 acts both to hold lens 18 and as a closure for the outer end of member 16, the latter being also threaded to engage the threads of said retaining cap. In the opposite narrowed end of the sleeve 24 100 an inside bushing 27, externally threaded, engages with lens-retaining ring 28, which is internally threaded, to hold lens 17 in position between them.

21 is a removable key which extends 105 through slot 22 in member 5 into an opening in member 4 provided for it, and 23 a knob on member 5, for the purpose of rotating the said members 4 and 5 as hereinafter described.

In the practical employment of my device it is operated as follows. Assuming the

lamp, with its associated parts, to be in the position shown in the drawings, and connected to a source of supply, and that the particular need of the moment calls for the concentration of the light in parallel rays, the operator takes hold of key 21 and rotates 4 over and back of, or partially back of, member 3. The light from 10 now flows in an unimpeded stream to the properly focused lens system in member 16, by which it is collected and concentrated into the comparatively small area of a spot light.

Where a wider area of evenly diffused light is required, the member 4 is moved 15 into its former position, key 21 withdrawn from the path of member 5, and the latter rotated back out of the light focus. The light will then be taken up by light-diffusing material 13 and diffused in the well known way.

Should it be desired to utilize all the light at the command of the operator directly, both members 4 and 5 are rotated out of the way, and the full power of the light source 25 employed in a flood or open light.

From the foregoing it will be seen that I have devised a simple and compact device for effectively controlling the shaft of light and readily increasing or decreasing its diameter. Furthermore, that my illuminating device possesses a number of novel features. It gives a spot light, a diffused light, and a glare light. It is constructed to prevent the light from coming out except where intended. The simplicity of its construction is such that it permits ready adjustment for the employment of any of the above forms of light by a simple manipulation of one or two elements. My new structure is so designed that it need never be taken apart, as by merely rotating members 4 and 5 over and back of the reflector 3, the lamp becomes accessible. Nevertheless the device is easily assembled and taken apart.

It is clear also that when members 4 and 5 are rotated over and back of member 3, the lamp can be easily removed and replaced through the opening thus formed between members 4 and 5 and member 3. This is a very valuable feature of my device. It makes it possible to remove and renew the lamp without disturbing or disarranging any other part of the construction, and makes the device a substantially unitary structure.

My improved mounting for the lenses illustrated in Fig. 3 also permits easy access to the same, as by simply unscrewing retaining cap 26 the sleeve 24 can be withdrawn bodily with the lens 17 and its associated parts.

It will be evident that various changes may be made in the construction of my device without sacrificing its advantages. The type which I have illustrated and described

herein is adapted to meet more especially the needs of the dental profession.

For the use of physicians generally a lamp which dispensed with member 4 and its diffusing section would be more appropriate. In such a lamp it is absolutely necessary to keep the light surrounded so as to prevent its emergence from any part of the device except where intended, to wit, the lens. This is accomplished by the co-operation of member 3 with member 5, that is, through the overlapping of members 3 and 5. This is a very important feature, as it eliminates all the objectionable defects possessed by nose and throat lamps now used by the medical profession. My device prevents the escape of light, thereby doing away with the reflections that always accompany the use of the open lights of the prior art, and so regulates it that it may be entirely directed to the place needed. For this style of lamp the tubular section 16 could be shortened and made to accommodate a glass or lens of any desired type.

I do not, therefore, limit myself to the exact construction shown, as various changes may be made therein without departing from the spirit of my invention or the scope of the claims appended hereto.

What I claim as new and desire to secure by Letters Patent, is:

1. A device of the character described having a stationary reflector which is substantially hemispherical, and two substantially hemispherical members having means for respectively attaching thereto light-diffusing material and lenses, said two members being spaced from each other and from the reflector and overlapping the latter and adapted to separately rotate thereover, and a light source positioned in front of the reflector, substantially as described.

2. A device of the character described having three substantially hemispherical members spaced from each other, one of said members being a reflector and having an opening in its wall for fastening therein a light source, the other two members being independently rotatable over said reflector, one of them being equipped with light diffusing material and the other having a tubular extension in which lenses are mounted, substantially as described.

3. A device of the character described having three substantially hemispherical members spaced from each other, one of said members being stationary and acting as a reflector, a light source positioned in front of the said stationary reflector member, the other two of said members overlapping said stationary member and adapted to separately rotate thereover, one being equipped with light diffusing material and the other having a tubular extension in which lenses are mounted, substantially as described.

4. A device of the character described having three substantially hemispherical members spaced from each other, one of said members being a reflector and having 5 an opening in its wall for insertion therein of a light source, the other two members being independently rotatable over said reflector, one of them being equipped with light diffusing material, a tubular extension 10 in the other, a sleeve in said extension, said sleeve having flanges on each end thereof, its outer flange engaging the circumference

of the tubular extension, a removable cap mounted on said extension and a lens held between said cap and flange, a removable 15 ring on the inner end of the sleeve, an adjustable member on the interior thereof contacting with the said inner flange, and a second lens held between said adjustable member and ring substantially as described. 20

In testimony whereof, I have signed my name to this specification.

ELLIOTT B. MABEE.
